DRAWING MECHANISM

Robert J. Adams, Thomaston, Ga., assignor of
one-half to Julian T. Hightower, Thomaston,
Ga.

Application June 28, 1935, Serial No. 28,906

2 Claims. (Cl. 19—130)

This invention relates to an improved means for drafting of textile fibers and the like which is adapted to be used on drafting machines such as slubbers, intermediates, speeders, jack frames and spinning frames. In the drawing out operation of textile fibers, it is very essential that the fibers in the roving should be gripped by the more rapidly revolving front rolls while their tail ends are still in the zone of retardation. This retardation causes a slight momentary tension in the fibers in drafting which causes it to straighten out and lie smooth and flat in the yarn produced. The ideal would be for each fiber to be retarded to an equal degree with the ordinary draft rolls described in the following specification. This is possible only if all of the fibers in the roving are of the same length. In practice, this condition is never encountered as all commercial cotton contains a considerable portion of short fibers. These short fibers are not retarded at all in the old method and are plucked through by the front rolls faster than the retarded long fibers. This tends to produce a bunch in the yarn made up of misplaced short fibers and followed by a thin place where the strong fibers should have been. It also tends to make a fuzzy yarn, as the short fibers are not laid straight by the retarding tension.

If it is attempted to bring the tail ends of the short fibers into the zone of retardation by setting the two lines of rolls closer to each other, the long fibers are positively gripped by both lines of rolls. As the two lines have different speeds, the fibers must either break or slip through the rolls. In either case the quality of the yarn suffers.

It is, therefore, an object of this invention to provide a third slip roll which is disposed between the front and intermediate rolls, said slip roll being mounted on the central or intermediate bottom roll and resting directly on top of and supported by the sliver or roving which is being drawn out. This roll is not weighted but is revolved by the yarn as it is being passed between the rolls. As has heretofore been stated, the short staple cotton of which a certain amount is present in all types of long staple cotton, will not reach from the bite of the front rolls to the bite of the intermediate rolls, but by providing a third roll disposed between the front rolls and the intermediate rolls, the short staple cotton is gripped at a point between the bite of the front roll and the intermediate roll, thereby causing the short fibers to align themselves with the long fibers in the strand of yarn. This will give

a more even number of fibers in a cross section of yarn, that is, the cross section will more nearly approach uniformity throughout.

It is a further object of this invention to provide a floating roll for maintaining the fibers of long staple and short staple cotton in perfect alinement which is easily installed and is very simple in its operation. By using a device of this nature, it is only necessary to re-locate the top central roll and insert the additional floating roll which can be done at very little expense.

It is still a further object of this invention to provide an additional top roll, in drawing machinery, which is self-adjusting as to position, the thickness of the sliver, roving or yarn determining the position of this additional top roll.

Some of the objects of the invention having been stated, other objects will appear as the description proceeds, when taken in connection with the accompanying drawing, in which:

Figure 1 is a vertical sectional view through a set of drawing rolls showing my invention applied thereto;

Figure 2 is a top plan view taken along line 2—2 in Figure 1;

Figure 3 is an isometric view of the added floating roll.

Referring more specifically to the drawing, the numeral 10 denotes a roll stand beam which has mounted thereon conventional roll stand 11 having rotatably mounted in the upper end thereof front or drawing roll 12, intermediate pressure roll 13 and back or feed roll 15. These rolls extend the length of the machine and are fluted and cooperate with top rolls 16, 17 and 18 in a drawing out operation of a sliver, roving and the like. Rolls 16, 17 and 18 are loosely confined in the position shown in Figures 1 and 2 by having a cap bar 19 at each end thereof, said cap bars having notches 20 in the side thereof, into which the tip portions 16a, 17a and 18a are adapted to fit. The cap bars are connected to each other by a suitable shaft 21 which is pivoted as at 22 to roll stand 11.

It is to be understood that a roll stand 11 will be disposed at spaced intervals along the top of roll stand beam 10. There are a plurality of sections of top rolls 16, 17 and 18, only one section being shown.

The cap bar 19 has a portion 19a connected thereto which maintains the upper top rolls 16 in position. This member has integral therewith a member 19b which fits in a suitable groove in the lower side of bar 19. The member 19b

has a slot 19c in the central portion thereof which is penetrated by a bolt 19d said bolt also penetrating the cap bar 19. When it is desired to reposition the top roll 16, it is evident that the 5 screw 19d can be loosened and the portion 19a will be free to be adjusted to a new position.

The roll stand 11 has adjustably mounted on the upper end thereof the conventional bearing portion 11a which is secured to portion 11 by 10 any suitable means such as a bolt 25 penetrating the member 11a and a suitable slot 26 in the upper end of roll stand 11. It is of course evident that when the two rear lower rolls 13 and 15 are desired to be adjusted with relation to 15 the front roll 12 that this adjustment can be made by manipulating the bolt 25.

It is seen that top rolls 17 and 18 have a saddle bar 27 normally bearing down on the central portion of these rolls and pressing down upon the 20 upper side of member 27 is one end of a saddle 28. The other end of saddle 28 normally rests upon the central portion of the upper front roll 16. Connected to the central portion of saddle 28 is the conventional stirrup 30 which extends 25 downwardly and is connected to a lever 31 which lever has one end thereof pivotally secured to a speakman screw 32, said screw 32 being secured to member 11. The right-hand end of lever 31 has mounted thereon a weighted member 33 30 which maintains a constant pressure upon the top rolls 16, 17 and 18.

In order to cause the short staple cotton, along with the long staple cotton, which is being worked to be gripped tightly at each end, I have provided 35 a floating roll 35 which normally rests upon the intermediate bottom roll 13 and is held in the position shown by lugs 38 projecting down from the lower side of portion 19a of the cap bar 19. These lugs are normally engaged by the 40 restricted end portions 36 and 37 on the end of roll 35. The strand of roving 40 passes through traverse bar 41 and then passes between the rolls 15 and 18 which are rotating at a constant speed. From these rolls it passes between the 45 rolls 13 and 17 which are rotating at a faster speed than rolls 15 and 18 and then the strands pass between the bosses 44 of floating roll 35 and the bottom fluted roll 13. From this point the 50 yarn passes between the front rolls 12 and 16 which are rotating at a still faster rate than the rolls 13 and 17. Floating roll 35 may be a steel roll or a covered roll. It has sufficient weight in itself to apply the proper pressure to the roving or sliver.

55 It is evident, by referring to Figure 1, that the bite or the point of tangency of the rolls 13 and 17 is farther away from the bite or point of tangency of the rolls 12 and 16, than it is from the bite or point of tangency of rolls 35 and 13. 60 By placing the upper roller 17 slightly backwardly on the cap bar, it is possible to insert the floating roll 35 and thereby allow the bite between the rollers 13 and 17 and the bite between the rolls 12

and 16 to control the long staple fiber, whereas, the bite between rolls 13 and 35 and the bite between the rolls 12 and 16 will control the short staple fiber to keep all of the fibers in perfect alignment. 5

It is of course evident that this principle and device can be used in slubbers, intermediates, jack frames and speeders, and in fact in any type of machinery where a strand or sliver is being drawn out. 10

In the drawing and specification there has been set forth a preferred embodiment of the invention, and although specific terms have been employed, they are used in a generic and descriptive sense only, and not for purposes of limitation, the scope of the invention being set forth in the appended claims. 15

I claim:

1. Drawing mechanism for textile slivers, rovings and the like having long and short fibers 20 therein, comprising lower front, intermediate and rear fluted rolls, upper front, intermediate and rear rolls, means for applying pressure to said upper rolls to press them against the lower rolls, an additional upper roll mounted between the 25 upper front and intermediate rolls, means for guiding said additional roll for movement towards and away from the lower intermediate roll along a plane normal to the plane passing through the longitudinal axes of the lower rolls, 30 and single means for simultaneously adjusting the guiding means for said additional roll along with the upper front roll with relation to said intermediate lower roll to change the points of contact of said additional roll with the intermediate lower roll independently of the position occupied by the intermediate rolls to correspond to the length of the short fibers present on the sliver, rovings and the like. 35

2. Drawing mechanism for fibers in sliver form 40 comprising front, intermediate and rear lower drafting rolls, front, intermediate and rear top rolls engaging the respective lower rolls, means for applying pressure to the top rolls to press them towards the lower rolls to thereby confine 45 the sliver passing between the lower and top rolls, an additional relatively heavy steel top roll mounted for sliding movement between the front and intermediate top rolls in a plane normal to a plane passing through the longitudinal 50 axes of the bottom rolls, whereby the sliver is contacted by said additional roll at a point substantially midway between the point where it is engaged by the intermediate rolls and the front rolls, to effect drafting of both the long and 55 short fibers in the sliver, and single means for adjusting the position of the front top roll and the additional roll at the same time with relation to the intermediate rolls to correlate the points of gripping the sliver on the lower intermediate 60 roll to the lengths of the short fibers in the sliver.

ROBERT J. ADAMS.
